UNITED STATES PATENT OFFICE.

ERNST CULLMANN, OF MUNICH-GLADBACH, GERMANY, ASSIGNOR TO THE FIRM
SPECK & BONSMANN AKTIENGESELLSCHAFT, OF HAAN, GERMANY.

SELF-CLOSING UMBRELLA.

Application filed March 30, 1927, Serial No. 179,470, and in Germany April 16, 1926.

The invention relates to a self-closing umbrella, in which the stretchers or spreaders are constructed in the shape of a so-called star-frame, i. e. in which the stretchers or 5 spreaders consist of plate-springs, which are so arranged that, when the umbrella is being opened, they are bent outwards laterally in spite of the elastic effect which they exercise, thereby imparting to the springs the tendency 10 to close the umbrella.

In the self-closing umbrellas with star-frame known up to the present, the release of the arresting- or locking-device which holds the umbrella open is effected by means 15 of a pulling-rod arranged within the hollow umbrella-stick and being connected to a small ring attached to the handle. Therefore in order to release the arresting or locking-device and thereby effect the automatic 20 closing of the umbrella it is necessary to pull back said small ring.

In contradistinction thereto the novelty of the invention essentially consists in providing a self-closing umbrella of the star-frame type with a drop-weight sliding along the umbrella-stick and intended to release the arresting- or locking-device. By these means the considerable advantage is obtained, that by merely turning down the 25 opened umbrella the drop-weight is caused to slide downwards, thereby releasing the arresting- or locking-device. On the other hand, the combination of stretchers or spreaders forming a so-called star-frame, which in itself is known per se, will cause, in a simple and reliable manner, an automatic closing of the umbrella after releasing the arresting- or locking-device through the medium of the elastic force exercised by the 30 plate-springs which are forced outwards laterally when the umbrella is opened. The elastic star-frame is for this reason specially suited for the construction of a self-closing umbrella and renders it possible, in conjunction with a drop-weight intended for 35 the purpose of releasing the arresting- or locking-device which holds the umbrella open, to construct an automatically closing umbrella which, in regard to simplicity, reliability and durability, attains such a degree of perfection as hitherto has been impossible. In connection herewith it is recommended to give the drop-weight the shape of a tip-cap which, when the um- 40

brella is closed, secures the ends of the ribs 55 and in this way closely presses the umbrella-cover against the umbrella-stick. Or, the lower end of the umbrella handle may be provided with a gap for the reception of the drop-weight, so that the latter is contained in the umbrella-handle and thereby rendered invisible.

Two embodiments of the invention are illustrated by way of example in the annexed drawing, in which 65

Fig. 1 shows the first example in a view of the end of the handle of a closed umbrella, partly in section,

Fig. 2 is a top-view of the opened umbrella, and 70

Fig. 3 shows the second example in a part-view with invisible arrangement of the drop-weight, also partly in section.

Fig. 4 is a sectional view of the opened umbrella inverted, and showing the drop weight in position to engage and release the latch device. 75

Fig. 5 is a sectional view through the umbrella stick on an enlarged scale and showing the latch device and drop weight in the same relative positions as in Fig. 4. 80

a represents the handle of an umbrella, to the lower end of which the umbrella-stick *b* has been attached. *c* is the well known runner, sliding along the umbrella-stick *b* and to which the stretchers or spreaders *d* for the umbrella-ribs *f* are fastened with one end each. The stretchers *d* each consist of two plate-springs *g*, *h* (Fig. 2), which are connected with each other at both ends and simultaneously jointed with their lower ends to the runner *c* and with their upper ends to the middle portions of the ribs *f*. Moreover, the individual plate-springs *g*, *h* of each stretcher are at their middle portions connected each with the plate-spring *h* or *g* of the adjoining stretcher by means of a strip *i* of sheet-metal bent around the plate springs. In consequence of this arrangement, when opening the umbrella, the individual plate-springs *g*, *h* of each stretcher are forced apart and caused to assume the shape of a star. The stretchers *d* possess for this reason the tendency to close the umbrella again, being, however, prevented therefrom by a well-known latch device *u* (Figs. 4 and 5) which holds the umbrella frame in the open or expanded position. This star-frame, be- 90

ing subject to the elastic effect of the springs, is therefore especially suitable for the construction of a self-closing umbrella, in which the arresting- or locking-device holding the umbrella open is released through the medium of a drop-weight k (Fig. 1). The drop-weight k consists of a cylindrical metallic body, which slides along the umbrella-stick b . When the umbrella is closed, the drop-weight k is positioned between the umbrella-handle a and the runner c , the latter engaging in a gap m of the drop-weight. The weight k is surrounded by a slidable jacket o of sheet-metal, the movement of which is limited by the cam p engaging in the longitudinal groove q of the drop-weight k . This jacket o serves as a tip-cap or catch for the ends of the ribs f , which, as will be seen from Fig. 1, are trapped by the lower part of the jacket o , when the umbrella is closed. The ends of the ribs may now, whenever required, be released in a well-known manner by pushing back the jacket o , thus allowing the umbrella to be opened.

Another example of performance and arrangement of the drop-weight is shown in Fig. 3, in which the drop-weight consists, in a similar manner as shown previously, of a cylindrical metallic body k^1 , which allows of being moved along the umbrella-stick. The lower end a^1 of the umbrella-handle a has, however, been provided with a gap s , which serves for the reception of the drop-weight k^1 , so that the latter is rendered invisible. When carrying the umbrella opened, i. e., when the part a^1 of the umbrella-handle is pointed upwards, the drop-weight k^1 rests upon the bottom t of the gap, whilst, when the umbrella is closed, it will be retained in the gap s by means of the ends of the ribs f .

The invention is, of course, not limited to the examples of performances represented herein, but other forms of execution are also possible. Especially the design and arrangement of the drop-weight may be effected in any other suitable manner and the enclosed or invisible drop-weight may also be utilized

in connection with umbrellas of other construction.

50

Claims:

1. A self-closing umbrella including a staff, a self-closing spring frame stressed on an opening movement thereof for a self-closing movement, a catch for holding the frame open, and a drop weight slidable upon the exterior of the staff for retracting the catch so as to permit the frame to close.

2. A self-closing umbrella including a staff having a handle, a self-closing spring frame stressed on an opening movement thereof for a self-closing movement, a catch for holding the frame open, and a drop weight slidable upon the exterior of the staff for retracting the catch so as to permit the frame to close, the said handle having a recess for the reception of the drop weight when the umbrella is closed.

3. A self-closing umbrella including a staff, a self-closing spring frame stressed on an opening movement thereof for a self-closing movement, a catch for holding the frame open, and a cylindrical drop weight slidable upon the exterior of the staff for retracting the catch so as to permit the frame to close, 70 said drop weight having a slidable jacket serving as a catch to receive and retain the ends of the umbrella ribs when the umbrella is closed.

4. A self-closing umbrella including a staff, a self-closing spring frame stressed on an opening movement thereof for a self-closing movement, a catch for holding the frame open, and a drop weight of annular form and slidably embracing the staff for retracting 85 the catch so as to permit the frame to close.

5. A self-closing umbrella including a staff, a self-closing spring frame of star-shaped type stressed on an opening movement thereof for a self-closing movement, 90 a catch for holding the frame open, and a drop weight slidable upon the exterior of the staff for retracting the catch so as to permit the frame to close.

In testimony whereof I affix my signature,
ERNST CULLMANN.
